DESIGN.

A. L. HALLIDAY.

CARPET.

No. 17,768.

Patented Oct. 11, 1887.

UNITED STATES PATENT OFFICE.

ARTHUR L. HALLIDAY, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 17,768, dated October 11, 1887.

Application filed September 8, 1887. Serial No. 219,183. Term of patent 3½ years.

To all whom it may concern:

Be it known that I, ARTHUR L. HALLIDAY, of New York city, in the county and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design consists of a body part, A, and a border part, B.

The body part A of my design consists of a 20 large central group, around which are scattered little bunches or groups of flowers, some resembling single sprays or stems. The central group has a solid central part, around which small flowers and leaves and grasses are gathered as if supported on a curving stem, 25 presenting the appearance of a wreath of flowers nearly encircling the middle portion of the group. A stem projects from the upper part, bearing larger circular flowers and several long curving leaves. Small buds hang from 30 the ends of this stem-work. The smaller sur-

rounding groups have a central flower or cluster of small star-shaped flowers, around which are leaves and grasses. Here and there between the groups or within them are spider-web figures.

My border B has an inner margin ornamented with triple-scroll forms and an outer margin of varying width ornamented with spider-web forms. The middle portion of the border consists of a curving stem branched at 40 the upper part. Flowers and leaves are thickly massed around the bottom of the stem work, and the curved branches at the top bear long curving leaves and larger circular flowers. To one side is a smaller cluster of leaves and 45 flowers, and here and there are spider-web forms.

What I claim as new, and desire to secure by Letters Patent, is—

1. In a design for carpets, the body A, substantially as shown. 50
2. In a design for carpets, the border B, substantially as shown. 55
3. The design for carpets, consisting of the body A and the border B, substantially as shown.

ARTHUR L. HALLIDAY.
